by *Charles F. Burgeson*
His Attorney.

UNITED STATES PATENT OFFICE.

CHARLES F. BURGESON, OF MINNEAPOLIS, MINNESOTA, ASSIGNOR TO GENERAL ELECTRIC COMPANY, A CORPORATION OF NEW YORK.

BUSHING-TERMINAL CONNECTER.

Application filed October 2, 1926. Serial No. 139,052.

My invention relates to bushing terminal connectors. Electrical apparatus such as a transformer or a circuit breaker is often immersed in oil in a casing which is provided with suitable insulating bushings for the leads which are brought out to terminals at the outer ends of the bushings, the external lines being connected to these terminals. The bushings are usually assembled from parts which are largely of fragile material such as porcelain and experience has shown that breakage of a bushing or other injury thereto is likely to be caused by the pull and vibration of an external line conductor connected to its terminal. This pull on the bushing may be in any one of various directions, either directly in line with the axis of the bushing or in some lateral direction, depending upon the direction in which the conductor leaves the bushing terminal. Sometimes a bushing terminal has been connected directly to a rigid and unyieldable external conductor such as a bus bar and in this case the extent and direction of the pull on the bushing depend upon the accuracy in the assembly of the bus bar and bushing. The transformer or other apparatus with which the bushing is associated is often very large and extremely heavy and if its supporting foundation is such as to permit it to settle at all, the pull on the bushing by the external conductor may be considerably increased and this is particularly apt to result in injury to the bushing if the apparatus settles unevenly and so as to tip away from the direction of the conductor connected to the bushing.

The general object of the invention is to provide a bushing with a yieldable connector interposed between the bushing terminal and an external conductor to relieve the bushing from excessive pull by the conductor. In its preferred form the connector comprises a yieldable, resilient helical conductor, its resiliency serving to absorb vibration and shock which may occur in the external conductor and its helical form serving to produce reactance may protect the apparatus from electrical disturbances in the external conductor.

Other objects and advantages will appear from the following description taken in connection with the accompanying drawing in which Fig. 1 is a bushing terminal con-

necter constructed in accordance with the invention and interposed between a bushing terminal and an external conductor, Fig. 2 shows an end view of the connector shown in Fig. 1 and Fig. 3 shows the connector as used in connection with a bushing of a large oil-immersed transformer.

Like reference characters refer to similar parts in the different figures of the drawing.

In its preferred form as shown in the drawing, the connector comprises a yieldable resilient helical conductor 10 formed of a flat strip of conducting material wound edgewise with spaced turns and with the greater cross sectional dimension of each turn at substantially right angles to the axis of the helix. The lower end of the connector is connected to the terminal 11 of a bushing 12 extending through a casing 13 such as is commonly used to enclose a large transformer. An external conductor 14 is connected to the upper or outer end of the connector 10. The external conductor 14 is shown in the drawing as extending laterally from the connector 10 so as to exert a lateral or sidewise pull on the connector 10 and bushing 12.

The flat cross sectional form of the turns of the connector 10 strengthens the connector against the lateral pull of the external conductor 14 but the connector will yield in any direction to prevent the pull which is transmitted from the external conductor to the bushing from becoming excessive from any cause such as tipping or settling of the casing 13 on its foundation. The reactance of the connector due to its helical form provides protection for the transformer and bushing against electrical disturbances in the external conductor 14. The connector 10 is also preferably sufficiently resilient to absorb vibration and shock from the external conductor 14 and substantially reduce transmission of such mechanical disturbances from the external conductor to the bushing. The connector thus provides both electrical and mechanical protection for the bushing.

The connector has been described in what is now considered its preferred form but various changes may of course be made within the scope of the invention as defined in the appended claims.

What I claim as new and desire to secure by Letters Patent of the United States is:

1. A bushing for encased electrical apparatus, said bushing having an outer terminal, an external conductor, and a yieldable connector interposed between said bushing terminal and said external conductor, said yieldable connector being in the form of an inductive helix.
- 10 2. A bushing for encased electrical apparatus, said bushing having an outer terminal, an external conductor, and a yieldable connector in the form of an inductive helix interposed between said bushing terminal and said external conductor, said connector

comprising a flat conductor with its greater cross sectional dimension substantially at right angles to the axis of the helix.

3. A bushing for encased electrical apparatus, said bushing having an outer terminal, an external conductor, and a yieldable resilient connector interposed between said bushing terminal and said external conductor, said connector comprising a flat resilient helical conductor with its greater cross sectional dimension substantially at right angles to the axis of the helix.

In witness whereof, I have hereunto set my hand this 22nd day of September 1926.

CHARLES F. BURGESON
